CLAIM

The ornamental design for a concrete vibrator motor and housing therefore, as shown and described.

DESCRIPTION

FIG. 1 is an isometric view of a concrete vibrator motor and housing therefore showing my new design;

FIG. 2 is a left side elevation view thereof;

FIG. 3 is a right side elevation view thereof;

FIG. 4 is top plan view thereof;

FIG. 5 is a bottom plan view thereof;

FIG. 6 is a front side elevation view thereof; and,

FIG. 7 is a rear side elevation view thereof.

The broken lines shown represent unclaimed subject matter and form no part of the claimed design.
